UNITED STATES PATENT OFFICE

ALFRED M. BAUMAN, OF SOMERSET, PENNSYLVANIA

COUPLER GAUGE

Application filed December 6, 1927. Serial No. 233,131.

This invention has reference to a combined coupler contour gauge and coupler height gauge, the primary object of the invention being to provide a gauge which may be employed in determining the height of a coupler when the car to which the coupler is secured, is loaded, or unloaded so that the coupler may be adjusted to meet the requirements of law.

- 19 A still further object of the invention is to provide means whereby lost motion in a coupler head due to wear may be determined, prior to placing the car equipped with the coupler, in use.
- 15 An important object of the invention is to provide a gauge of this character which is collapsible and one which will be accurately used to accomplish its purpose.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

- 30 Figure 1 is a plan view of a gauge constructed in accordance with the invention showing the same in its folded position.

Figure 2 is a side elevational view showing the gauge assembled for use.

- 35 Figure 3 is a sectional view taken on line 3-3 of Figure 2.

Figure 4 is an enlarged sectional view taken on line 4-4 of Figure 2.

- 40 Figure 5 is a sectional view taken on line 5-5 of Figure 4.

Figure 6 is an enlarged elevational view of the vertical measuring bar.

Figure 7 is a sectional view taken on line 7-7 of Figure 1.

- 45 Figure 8 is a sectional view taken on line 8-8 of Figure 2.

Referring to the drawing in detail, the numeral 5 designates the body portion of the gauge which is formed preferably of a length 50 of heavy sheet metal, the same having its side

edges bent upwardly defining lateral flanges 6 and 7 respectively, the end portions of the flanges being bent into engagement with each other as shown by Figure 8 where they are riveted in such position by means of the 55 rivets 8.

Ears 9 extend upwardly from the flanges 6 and 7 and are formed with openings to receive the rivets 10 that extend across the body portion for purposes to be hereinafter more 60 fully described.

Secured to the body portion 5 at a point intermediate the ends thereof, is a socket member 11 which has a slot formed in one wall thereof to receive the rib 12 of the vertical gauge bar 13 so that when the gauge bar is positioned in the socket member, the rib, 65 lying within the slot, will hold the vertical gauge bar 13 in an upright position.

As clearly shown by Figure 4, the walls of 70 the socket member 11 are formed with openings, one of the openings being threaded to receive the threaded extension 14 of the bolt 15 formed with a knurled head 16, whereby the bolt may be readily and easily removed or 75 replaced. Registering with the openings in the socket member is an opening formed in the vertical gauge bar 13 so that when the bolt 15 is positioned, it will pass through the registering openings of the socket member 11 and 80 gauge bar 13 so that the gauge bar will be secured in position.

An opening 17 is formed in the bolt 15 and is designed to accommodate a cotter key or the like to insure against the bolt becoming 85 accidentally displaced. Formed on the vertical gauge bar 13 are graduations 18 opposite which certain indicating characters and numbers are formed so that when the vertical gauge bar is positioned, in front of a coupler, the vertical play of the coupler caused by 90 wear may be determined and should the wear be too great to insure safety, the coupler may be readily repaired.

It will be seen that the indicating characters and numbers are arranged in groups so that the gauge may be employed in connection with standard gauge rails, or rails of various sizes. Secured to the vertical gauge bar 13 by means of the chain 19, is a gauge 95 100

which is of a length to closely fit within the space between the coupler knuckle and knuckle guard, and it will be obvious that by positioning this member 20 between the 5 knuckle and knuckle guard, lateral play caused by wear of the knuckle or its supporting pin may be determined in examining the knuckle.

This gauge bar 13 is substantially narrow 10 and is formed with bayonet slots 21 to accommodate the rivets 10 when the gauge bar is positioned over the body portion in its folded condition, whereupon the gauge bar is held or locked in position.

15 From the foregoing it will be seen that due to this construction I have provided a gauge of a construction which may be readily and easily carried from place to place and readily set up for use in gauging couplers to determine 20 whether or not the couplers are rendered inoperative by the wear.

I claim:

1. In a gauge of the class described, an elongated body portion adapted to rest on 25 the rails of a railway track, a socket member having a vertical slot formed in one wall thereof, a gauge bar fitted in the socket member and having a lateral vertical rib fitted in the slot to restrict movement of the gauge 30 bar, and means extending through the socket member and gauge bar for securing the gauge bar within the socket member.

2. In a gauge of the class described a body portion formed of a length of sheet metal 35 having its side edges bent upwardly defining lateral flanges, rivets connecting the flanges, a socket member on the body portion, a gauge bar adapted to be fitted in the socket member, one edge of the gauge bar having bayonet 40 slots, said gauge bar adapted to be removed from the socket member and positioned longitudinally of the body portion between the flanges, and said bayonet slots adapted to receive the rivets when the gauge bar is in its 45 inactive position.

In testimony that I claim the foregoing as my own, I have hereto affixed my signature.

ALFRED M. BAUMAN.
